UNITED STATES PATENT OFFICE.

HERMAN C. TORDSEN, OF LAKEFIELD, MINNESOTA, ASSIGNOR OF ONE-HALF TO E. J. STOTEREAU AND FRED K. GAGE, BOTH OF LAKEFIELD, MINNESOTA.

GRAIN-CAR DOOR.

Application filed April 17, 1926. Serial No. 102,804.

This invention relates to doors for grain cars, and its primary object is to provide a folding door, of simple, strong and durable construction, which is adapted when in closed position to seal the door opening in a substantially leak-proof manner, and which is adapted to be easily and conveniently folded and moved laterally beyond one side of the doorway to uncover the latter.

10 A further object of the invention is to provide a folding door suspended by hangers which is movable toward and from the door jambs relative to the hangers to close tightly against suitable surfaces of the jambs and to permit movement of the door backwardly from the jambs so as to permit it to be shifted into and out of closing position.

15 A still further object of the invention is to provide a folding door composed of hinged sections having a bottom opening through which grain may be discharged preliminarily to and to permit opening of the door, and which is provided with a lever so constructed and arranged as to facilitate the folding of the door, which lever is also adapted to serve as a brace for the door sections in the folded and unfolded conditions of the door.

20 With these and other objects in view, the invention consists of the features of construction, combination and arrangement of parts, hereinafter fully described and claimed, reference being had to the accompanying drawings, in which:

25 Figure 1 is a sectional view of a portion of a grain-car viewed from the outside, including one of the doorway openings, with the improved grain door attached and in closed position.

30 Figure 2 is a similar view of the parts viewed from the inside, and showing in full lines the door in closed position, and in dotted lines the door in retracted position.

35 Figure 3 is a vertical section taken on the line 3—3 of Figure 1, showing the door in closed position.

Figure 4 is a view similar to Figure 3 showing the door folded and supported in retracted position.

40 Figure 5 is a detail view showing a feature of construction.

45 Referring now more particularly to the drawings, 1 designates a portion of a grain car or other structure having an opening or doorway 2 therein, and 3 are jambs or posts located at opposite sides of the doorway and

rabbeted or otherwise suitably constructed to provide the flanges or ledges 4 against which the door is adapted to abut to effectually seal the doorway against the escape of grain between the posts or jambs and the side edges of the door.

50 The door embodying my invention comprises a series of superimposed sections 5, 6, 7 and 8, which are preferably of the same superficial dimensions and are adapted to abut in edge to edge contact and to lie in the same vertical plane when adjusted to close the doorway or opening 2. The door structure as a whole is supported by hangers 9 provided with rollers 10 to travel upon a horizontal track 11, said track being arranged above the doorway and extending beyond one side thereof to permit the door to be moved to retracted position. Each of these hangers is provided with a U-shaped 75 guard 12 underlying the track 11 to prevent their upward displacement and the jamming of the rollers 10 from the track. Brackets 13 support the door structure from the portions 12 of the hangers, said brackets being 80 secured at their lower ends in any suitable manner to the upper door section 5.

85 The track 11 is arranged flush with the top of the doorway and a suitable distance inside the vertical line thereof, so as to adapt the door, when in the folded position shown in Figure 4, to travel along said track parallel with and just inside of the wall in which the doorway or opening 2 is formed. The brackets 13 have horizontal arms 14 at their upper ends, which arms are provided with transverse slots 15 to receive bolts or other suitable fastenings 16 passing through the guard portions 12 of the hangers 9. The slots 15 provide for a sliding adjustment between the suspended door and the hangers 9, whereby, when the door is arranged opposite the opening 2, said door may be moved toward and from said opening, for the purpose of bringing the door into engagement 90 with the ledges 4 for a tight closing action or to permit the door to be thrown inwardly beyond the line of the doorway in order that it may be moved to a retracted position.

95 By this means the door may be adjusted to close the opening 2 tightly against the escape of grain while it is also adapted to be adjusted to permit of its movement into and out of closed position without interference from the posts or jambs 3.

The bottom section 6 of the door is provided with a grain discharge opening 17 which occupies the greater portion of the area of said door section, leaving the latter in the form of a marginal frame to receive a gate 18 adapted to fit within the opening. This gate 18 is hinged at its upper edge to the section 6, as indicated at 19, to swing open in an outward direction and is provided at its lower edge with latches 20 to engage keepers 21 at the base of section 6, whereby the gate may be firmly secured in closed position against the escape of grain. The opening 17, which is normally closed by the gate 18, provides an outlet through which a certain amount of grain may be allowed to discharge for inspection whenever desired, and it also provides a means whereby, through the full opening of the gate 18, all the grain lying immediately in rear of the lower door sections may be permitted to discharge to adapt the door sections to be folded upon themselves for a door collapsing and opening action. It will be understood, of course, that when the car is filled with grain the grain banks tightly against the rear of the door, thus preventing the door from being folded and opened under normal conditions, but by opening the gate 18 the bulk of grain in rear of the door may be allowed to discharge, thus adapting the door to be easily and conveniently folded and opened for the removal of the remainder of the grain from the car.

The upper section 7 of the door is hinged at its upper edge to the top section 5 on the inside, thus adapting the said section 7 to be swung upwardly on the inner side of the section 5 and in parallel relation therewith. The two intermediate sections 7 and 8, however, are hingedly connected at their adjacent edges on the outside of the door, so as to permit the lower intermediate section 8 to be swung downwardly on the inside of the folded section 7 and in parallel relation therewith. The bottom door section 6 is hinged at its upper edge on the inside of the door to the lower edge of the door section 8 so as to adapt it to be swung inwardly and upwardly on the inner side of the folded door section 8 and in parallel relation therewith when desired. A lever 25 is fixed at its lower portion upon the outer surface of the door section 7 and has its upper free end arranged to extend against the outer face of the door section 5 when the door sections are in closed position. The said upper portion of this lever serves as a handle by means of which the lever may be gripped for actuation, and said upper portion of the lever is provided with an opening 28 for passage of a staple or other like keeper member 29 on the door section 5, through which staple or keeper may be passed a fastening pin 30, whereby the lever may be employed

to lock and rigidly connect the door sections 5 and 7 against swinging or collapsing movement, whereby the upper half of the door will be held solid and rigid against the pressure of the grain, the lower door members being held solid and rigid by the pressure of the grain holding them against the jambs or ledges 4, so that in service an absolutely rigid and secure type of door will be provided.

Figure 1 shows the door in closed position, from which it will be seen that the door sections are in vertical alignment and abut against the inner faces of the flanges or ledges 4, thus closing the doorway against the escape of grain. In opening the door to permit removal of the grain, the gate 18 may first be opened to permit discharge of the bulk of grain lying immediately in rear of the door, after which the door may be folded and moved to retracted position. In folding the door the fastening pin 30 is disconnected from the keeper 29 and its upper end grasped and pulled outwardly and downwardly and then forced inwardly, so as to cause the section 7 to swing upwardly and upon the inside of the section 5, and the section 8 to swing upwardly and upon the inside of section 7, the rigid portion of lever 25 thus lying between sections 5 and 7, while the handle portion thereof is reversed so as to lie against the outer face of the section 6 and to overlap the gate 18. In such position of the handle end of the lever 25 the opening 28 therein is brought into engagement with a keeper 31 adapted to receive a fastening pin 32 on the gate 18, whereby the handle end of the lever may be locked to the gate 18, thus holding the section 6 rigid with section 8, and in vertical alignment therewith, so that all three sections 6, 7 and 8 will be rigidly coupled to permit the folded door to be run backward and forward on the trackway 11, which folding action is sufficient under all normal conditions to enable the door to be moved backward and forward without interference from the grain. However, in order to afford greater clearance, and to permit of the discharge of a large amount of grain lying in rear of the door, the gate 18 may be first opened to allow discharge of as much grain as possible and to permit the door section 6 to be swung upwardly on the inner side of section 8 to permit a still larger amount of grain to discharge, after which the portions of the door may be folded for backward and forward movement to the position shown clearly in Figure 4 and in the manner before described. By this means any portion of grain liable to interfere with the opening of the door may be discharged preliminarily to the door opening movement, after which the door may be folded and its sections rigidly held together for a ready and convenient

movement back on the trackway to retracted position and subsequent movement thereafter to a position in alignment with the door opening. The adjacent edges of the 5 respective door sections may, as shown, be suitably scarfed or halved in order to adapt them to lap when in closing position to seal all crevices against discharge of grain or collection of any grain or other foreign material therein.

If desired, suitable means may be provided to support the folded door in such position when retracted. For this purpose I have indicated in Figure 3 a support 33 any 15 number of which may be used. These supports may be suitably secured at their upper ends to the car roof and depend therefrom and are provided at their lower ends with feet or staples 34 against which the lower 20 edge of the folded door may bear, as will be readily understood.

From the foregoing description, taken in connection with the drawings, the construction and mode of my improved grain car door will be readily understood, and it will 25 be seen that a door of this character is provided which is not only simple in construction, and adapted to be readily and conveniently opened and closed, but which is 30 also adapted to securely seal the door opening when in applied position and is rigidly braced when in such position against any possibility of damage or breakage under pressure of the bulk of grain. Also it will 35 be seen that the invention provides a door which may be readily and conveniently folded, moved into and out of operative

position, and supported against collapse when in retracted position.

Having thus fully described my invention, 40 I claim:

1. The combination with a structure having a door opening, and a trackway, of a door mounted to travel upon the trackway, said door comprising upper and lower sections and a pair of intermediate sections, the upper and lower sections being hinged 45 to the respective intermediate sections on the inside and the intermediate sections being hinged to each other on the outside, and a lever fixed to the outer side of the upper intermediate door section and having a portion serving as a handle adapted to overlap upon the upper and lower door sections in the unfolded and folded positions of the 50 door respectively, and means for securing said handle end of the lever to said upper and lower door sections.

2. The combination with a structure having a door opening, of an overhead track, 60 hangers mounted to travel on said track, brackets slidably connected with the hangers, and a door comprising upper, lower and intermediate hinged sections, and a lever connected to the upper intermediate hinged 65 section and having an end serving as a handle adapted to be arranged to overlap the top section or bottom section in the unfolded and folded positions of the door respectively and to be locked to said respective 70 sections.

In testimony whereof I affix my signature.

HERMAN C. TORDSEN.
